UNITED STATES PATENT OFFICE.

JOHN L. SOMMER, OF NEWARK, NEW JERSEY, ASSIGNOR TO J. L. SOMMER MFG. CO.,
A CORPORATION OF NEW JERSEY.

DESIGN FOR A BOTTLE-OPENER.

42,306.

Specification for Design.

Patented Mar. 12, 1912.

Application filed September 14, 1911. Serial No. 649,379. Term of patent 14 years.

To all whom it may concern:

Be it known that I, JOHN L. SOMMER, a citizen of the United States, residing at Newark, in the county of Essex and State of New Jersey, have invented a new, original, and ornamental Design for Bottle-Openers, of which the following is a specification, reference being had to the accompanying drawing, forming part thereof.

Figure 1 is a side elevation of a bottle

opener of my new design, and Fig. 2 is an edge view of the same.

I claim:

The ornamental design for a bottle opener, as shown.

JOHN L. SOMMER.

Witnesses:

J. G. COLEMAN,
ELIZABETH G. KING.
